United States Patent

Des. 242,501
Patented Nov. 23, 1976

242,501

LICENSE PLATE

James V. Bruckner, Conway, Ark., assignor to
Metal Stamping Corp., Conway, Ark.

Filed Oct. 16, 1975, Ser. No. 622,244

Term of patent 14 years

Int. Cl. D20—03

U.S. Cl. D96—12 E

FIG. 1

FIG. 2

FIG. 3

FIG. 1 is a front elevational view of a license plate, showing my new design;

FIG. 2 is a top plan view thereof; and

FIG. 3 is an end elevational view looking from the right.

The broken line disclosure in FIGS. 1, 2 and 3 is for illustrative purposes only.

I claim:

The ornamental design for a license plate, as shown and described.
